YARN FEEDING MECHANISM FOR KNITTING MACHINES

Filed Dec. 6, 1924

UNITED STATES PATENT OFFICE

MAX C. MILLER, OF CUMBERLAND, RHODE ISLAND

YARN-FEEDING MECHANISM FOR KNITTING MACHINES

Application filed December 6, 1924. Serial No. 754,362.

The invention relates to yarn feeding mechanism for knitting machines and has to do particularly with machines that produce fabric by relative reciprocation of the needle bed 5 or cylinder and the cams or devices which form the knitting wave to which the yarn is fed by the yarn eye or eyes.

Machines of this type may be flat or circular and the relative reciprocation between 10 the needles and the yarn feeding and cam elements may be effected by reciprocation of the knitting cams and yarn eye or of the needle supporting bed or cylinder.

On machines upon which fabric is produced 15 through a reciprocation of either the cam elements or the needle support, it is customary to continue the stroke of the reciprocating elements until the cam elements have cleared the active needles and until the yarn 20 feeding element has passed beyond the last active needle a sufficient distance to insure the last needle getting its yarn. This necessitates the use of take-ups, one for each yarn being used, in order that the surplus slack 25 yarn between the yarn feeding element and the last active needle may be taken up during the relative reciprocation between the needles and the cam and yarn feeding elements. The use of such take-ups is objectionable since 30 they limit the speed at which the machine may be operated and also require the use of a high grade of yarn which will stand the strain of the take-up action. Their use is also objectionable since they cause the last 35 needle or needles knitting in any given stroke to knit loops of a size differing from those knit by the needles more centrally located in the series of active needles, such difference in the size of the loops being due to the varying 40 tension placed upon the yarn by the action of the take-up.

The use of take-ups is particularly objectionable on double bank straight bar machines 45 of the Lamb or Burson type which are designed to knit tubular fabric, since they render it extremely difficult and, on fine gauges, practically impossible, to knit the end needle loops of the same length and appearance as 50 the loops in the parts of the fabric knit by

the more central needles of the knitting series.

It is the primary object of the present invention to provide a yarn feeding mechanism for machines operating either wholly or in 55 part to produce the fabric by relative reciprocation of the needles and cam elements which causes a knitting wave to travel back and forth along a single or double series or bank of needles. It is a further object of 60 the invention to provide a mechanism of this character which is well adapted for application to a double bank straight bar machine of the type above referred to although it would be understood that the invention is not 65 confined in its application to this type of machine.

To these ends the invention comprises the 70 features of construction and combination of parts hereinafter described and specified in the claims.

In the drawings one embodiment of the invention is shown applied to a double bank straight bar machine adapted for knitting either flat or tubular fabric. In these drawings Figure 1 is a transverse sectional view showing so much of the machine of this type as is necessary to illustrate the application of the present invention thereto; Fig. 2 is a partial elevation looking toward the left in Fig. 75 1, the right hand needle bed and parts supported thereby as well as the web holders being omitted for the sake of clearness; Fig. 3 is a partial plan view of parts illustrated in Fig. 1; and Fig. 4 is a view in side elevation 80 of the parts shown in Fig. 1 looking towards the right.

In the machine illustrated in the drawings, two series of banks of needles are supported 85 and guided in the two opposed needle beds 90 1 which are or may be of the usual construction. The knitting wave which, in knitting tubular fabric, travels along one bank in one direction and back across the other bank in the opposite direction and which in knitting 95 flat fabric travels back and forth along one of the banks, is formed by the usual cam elements comprising the needle advancing cams 9, 9^a which may be rendered alternatively active or inactive and the stitch cam 8, these 100

cam elements being carried, as is usual, by cam bars 6 mounted to slide in cam slide bearings 2 secured to the needle beds. Vertically reciprocating web holders which form no part 5 of the present invention are indicated at 1A.

The mechanism for feeding the yarn or 10 yarns to the needles comprises a yarn finger 4^b provided with one or more guides or thread eyes for delivering the yarn to the needles of the knitting wave, two such thread guides or 15 eyes being indicated at 4^c relatively arranged for plaiting. The yarn finger is provided with a vertical shank mounted to rotate in a bearing in the yarn carrier 4 about a vertical axis located in the center line of the machine 20 midway between the needle beds. The yarn carrier 4 is mounted to slide on a cylindrical bar or rock shaft 3 which is mounted in brackets 2A formed on the cam slide bearings 2. The yarn carrier is provided with a lug 4^d 25 resting on one of a pair of cylindrical bars or rock shafts 11 which are mounted in the brackets 2A above the needle bed. The yarn finger may be turned through an angle of 180 degrees to bring the yarn eyes into position to 30 deliver the yarn to either one or the other bank of needles by means of a rack 4^a mounted in the upper end of the yarn finger bearing and provided with rack teeth engaging teeth 35 formed on the upper end of the yarn finger shank. The rack may be shifted to shift the yarn carrier from one side to the other by means of two bars 10 extending longitudinally of the machine and carried upon arms 12 40 secured to the ends of the cylindrical bars 11. The arms 12 are connected by links 10^a and are actuated through a link 10^b from any suitable form of pattern mechanism such as is commonly used in the knitting art to automatically effect changes during the knitting operation. 45 The yarn carrier and thread eye are caused to travel along the series of active needles in advance of the knitting cam to deliver yarn to the needles in the knitting wave by the engagement of a plate 7 carried by the cam slides 6 and arranged to engage a latch lever 5 which is pivoted at 5^a on the yarn carrier and is held in engagement with the bar 3 by a spring 5^c connecting it with a finger depending from the yarn carrier. The spring not 50 only holds the latch in engagement with the bar 3, but also holds the lug 4^d of the yarn carrier in engagement with the left hand bar 11. The latch 5 is V-shaped at 5^b to engage notches 3^a formed in the bar 3. The operation is as follows: As shown in 55 Figs. 1 and 2, the yarns are being fed to the left hand bank of needles and the lever 3A which is secured to the end of the bar 3 is in the full line position marked X so that the notches 3^a will be in position to be engaged by the latch 5. The notches are located in such position that they will be engaged by the latch 5 when the thread eyes have passed beyond the last active needle and is located be-

tween that needle and the next needle beyond, in case there are inactive needles beyond the end of the active series, or in case the last active needle is the end needle of the series, at a distance beyond this needle substantially 70 one half the gauge or distance between two needles. When the latch 5 reaches the notch 3^a at the left, it enters the notch, thereby swinging into the dotted line position of Fig. 1 and disengaging itself from the plate 7 so that the travel of the thread finger is accurately and positively arrested in a definite position with the yarn eye or eyes just beyond the last active needle or between it and the adjacent inactive needle. The travel of the cam slide 6 continues to complete the travel of the stitch cam and knitting wave across the series of active needles and to carry the inactive needle elevating cams 9^a to a position clear of the needles. During this continued travel of the stitch cam, the needles near the end of the series draw the yarn which was delivered to them by the yarn eyes before they were arrested by the engagement of the latch 5 with the notch 3^a. The continued travel 75 of the cam slide after the thread finger has been arrested carries the plate 7 beyond the latch 5 to the left so that it is in position to act on the latch during the return stroke of the slide toward the right. Before the plate 80 90 reaches the latch in the return stroke of the cam slide, the bar 3 is rocked into the position indicated at Y, Fig. 1, by pattern mechanism acting through a link 3^b connected with the arm 3A on the end of the bar. This movement of the bar swings the latch into full line position and into the path of the plate 7 so that the return travel of the thread finger is started when the knitting wave formed by the now active needle raising cam 9^a and stitch cam 8 has reached the proper relation with the thread finger. The thread finger now 100 travels toward the right along the series of active needles with the knitting wave until the latch 5 reaches the notch 3^a at the right, the bar 3 in the meantime having been returned to the position indicated at X in Fig. 1, and then the latch enters this notch and arrests the traverse of the thread finger and holds it in definite position while the cam 105 slides complete their stroke to the right. 110

In case a flat fabric is being knit on the left bank of needles, the yarn finger will remain in the position indicated in Fig. 1 with the yarn eyes in position to feed their yarns to this series of needles. If a tubular fabric is being knit, the thread finger will be swung through an angle of 180 degrees after the stitch cam has passed beyond the active needles. This will bring the eyes into position to deliver their yarns to the needles in the right hand or front bank and during the stroke of the cam slides toward the right the needle raising cam 9^a for the right or front bank will be rendered active to cause the knit- 115 120 125 130

ting waves to travel toward the right along the front bank. At the end of the stroke in this direction, the thread finger will be swung backwards to the position indicated in Fig. 1 to deliver its yarns to a knitting wave formed in the left hand or rear bank during the succeeding stroke of the cam slides toward the left.

In either case, that is, whether knitting flat or tubular fabric, there will be no surplus slack yarn between the yarn eye or eyes and the end needle of the active series at the completion of the stroke of the reciprocating element or after the knitting wave has completed its traverse along the needles and the yarns 10 may be uniformly and accurately fed to all the needles under even tension and in such manner that the needles throughout the active series whatever its lengths, may draw 15 uniform or the desired length of loops and thus a fabric produced having the desired and predetermined characteristics throughout.

As shown in Fig. 2, the lines W indicate the last needles in the needle beds and the notches 20 3^a in the bar 3 are located just beyond these needles. It will be understood, however, that the bar may have a number of sets of notches, any set of which may be brought into active 25 relation with the latch 5 by rotation or adjustment of the bar as, for instance, by shifting it in the arm 3^a or by proper action of the pattern mechanism. These notches may be arranged to positively stop the relative traverse of the yarn eyes along the needles at any 30 desired point and the points of stopping may be varied at different strokes as, for instance, in knitting a narrowed or widened fabric.

While the invention has been shown embodied in a double bank straight bar latch 35 needle machine in which the traverse of the knitting wave and yarn eye relative to the needles is effected by reciprocation of the knitting cams and yarn eye, and in which the traverse of the yarn eye relative to the needles is arrested by arresting the movement of 40 the yarn eye, it will be understood that the invention is not confined in its application to this type of machine or to this manner of securing the traverse of the knitting wave and 45 yarn eye or to this manner of arresting the traverse of the eye relative to the needles. For instance, if the broader features of the invention were to be embodied in a machine in which the traverse of the knitting wave and 50 thread eye along the needles is secured by reciprocation of the needles rather than of the cam elements and thread eye, then the 55 traverse of the thread eye with relation to the needles might be effected by causing the 60 thread eye to travel with the needles after it had reached a point just beyond the last active needle, the traverse of the eye with relation to the needles thus being arrested during 65 the completion of the stroke of the needles.

What is claimed is:

1. In a straight knitting machine the combination with a bank of needles, and a reciprocating cam slide, of a yarn carrier, a latch on the carrier, a guide bar on which the carrier slides, and notches in the bar with which the latch engages to arrest the movement of the carrier and means for disengaging the latch from the notches. 70

2. In a knitting machine, the combination with a bank of needles, of a yarn carrier movable back and forth across the needles, a reciprocating slide, a latch on the carrier for connecting the carrier and slide, a stop to engage the latch and stop the carrier during the continued movement of the slide, and means 80 for moving the latch to release the slide and engage the stop. 75

3. In a knitting machine the combination of a bank of needles, of a yarn carrier movable back and forth across the needles, a latch on the carrier, a slide provided with a plate 85 on the carrier, a stop to engage the latch and stop the carrier during the continued movement of the slide, and means for moving the latch to release the slide and engage the stop. 90

4. In a knitting machine the combination with a bank of needles, of a yarn carrier movable back and forth across the needles, a reciprocating slide, a latch on the carrier forming an abutment to be engaged by abutments 95 on the slide, stops to engage the latch and stop the carrier during the continued movement of the slide in each direction, and means for moving the latch to release the slide and 100 engage the stops. 85

5. In a knitting machine the combination with a bank of needles, of a yarn carrier movable back and forth across the needles, a reciprocating slide, a latch on the carrier forming an abutment to be engaged by abutments 105 on the slide, a bar provided with notches with which the latch engages to arrest the movement of the carrier and release the slide, and means for moving the bar to disengage the 110 latch from the notches and move the latch into slide engaging position. 105

6. In a knitting machine the combination with a bank of needles, of a yarn carrier movable back and forth across the needles, a reciprocating slide, a latch on the carrier for connecting the carrier and slide, a bar provided with notches with which the latch engages to arrest the movement of the carrier 115 and release the slide, and means for rocking 120 the bar to disengage the latch from the notches. 115

In testimony whereof I have signed my name to this specification.

MAX C. MILLER. 125
